WILLIAM JAMES ALBERT LONDON, OF MANCHESTER, ENGLAND, ASSIGNOR, BY MESNE ASSIGNMENTS, TO THE COLONIAL TRUST COMPANY, TRUSTEE, OF PITTSBURGH, PENNSYLVANIA, A CORPORATION OF PENNSYLVANIA.

ELASTIC-FLUID TURBINE.

1,095,506.

Specification of Letters Patent.

Patented May 5, 1914.

Application filed April 18, 1906, Serial No. 311,482. Renewed October 30, 1912. Serial No. 728,733.

To all whom it may concern:

Be it known that I, WILLIAM JAMES ALBERT LONDON, a subject of the King of England, residing at Trafford Park, Manchester, 5 England, have made a new and useful Invention in Elastic-Fluid Turbines, of which the following is a specification.

This invention relates to elastic fluid turbines.

10 The invention, broadly, consists of combining with a primary or initial turbine a plurality of independent turbines, each of which is adapted to be connected in series with and receive motive fluid from the primary turbine to which motive fluid is supplied in automatically regulable amounts.

The embodiment of my invention as illustrated in the drawings accompanying this application comprises a turbine provided with 20 an initial stage or section to which motive fluid is supplied through governor-controlled nozzles, and a plurality of secondary stages, or sections, each of which communicates with the initial section and is adapted to 25 fractionally expand, in successive steps, the motive fluid delivered from the initial section and to abstract the available energy due to the said expansion by impulse and reaction. The rotor element of each stage, or 30 section, is mounted on the turbine shaft and an automatic valve is provided between the initial stage and the secondary stages which varies the number of secondary stages in communication therewith in accordance with 35 the load demand.

The object of this invention is the production of a turbine that will operate efficiently under a wide range of loads, and in which automatic means are utilized for proportioning the motive fluid supply in accordance 40 with the load demand.

A further object is the production of a turbine in which the number of working stages are varied in accordance with the load 45 demand.

A still further object is the production of a turbine in which means are utilized for increasing the effective working passages in accordance with the amount of motive fluid 50 supplied.

These and other objects I attain in a turbine embodying the features herein described and illustrated.

In the drawings accompanying this appli-

cation and forming a part thereof, Figure 1 55 is a partial longitudinal section of a turbine embodying my invention. Fig. 2 is a partial side elevation of the turbine shown in Fig. 1. Fig. 3 is a transverse section along the line 4—4 of Fig. 1.

The turbine consists of an initial stage, 5 and secondary stages 6, 7, 8 and 9 inclosed within a stationary casing 10, which is formed in a number of annular sections. The rotor element of each stage is rigidly 65 mounted on a shaft 11 which is journaled outside of the casing 10. The initial stage 5 receives motive fluid from a group of governor-controlled nozzles 12 and communicates with a receiving chamber 13. The 70 secondary stage 6 communicates directly with the receiving chamber 13 and the stages 7, 8 and 9 communicate therewith through passages 14, 15 and 16, formed within the casing 10.

The initial stage comprises a wheel 18, mounted on the shaft 11 and provided with two rows of peripherally-mounted impulse blades 19. A row of stationary directing vanes 21 is mounted on the casing 10 intermediate of the two rows of moving blades 19 and is adapted to receive motive fluid discharged from one row of blades and deliver it in the most efficient manner to the other row. The motive fluid supply nozzles 12 are arranged at one end of the turbine and supply motive fluid to the initial stage 5 and are arranged to convert a portion of the pressure energy of the motive fluid into kinetic energy in the form of velocity by 90 expanding the fluid from the initial pressure to a predetermined lower pressure and the impulse blades 19 are adapted to convert the fluid velocity into available energy. The motive fluid discharged from the initial 95 stage enters the receiving chamber 13, which is formed within the casing between the initial stage and an inclosing wall of the secondary stage 6. The stage 6 and each of the stages 7, 8 and 9 comprise a rotor ele- 100 ment 22, rigidly mounted on the shaft 11 and inclosed within a casing formed integrally with the casing 10. A wall 23 of the stage casing extends inwardly toward the shaft 11 and a port 24 is maintained around 105 the shaft and between it and the inner periphery of the wall. A packing 25, which consists of interleaving grooves and ridges

105

formed on the shaft and stationary casing, seals the joint between the shaft and a wall 26 of the stage casing.

Each rotor 22 is provided on both sides 5 with rows of suitably mounted radially-arranged blades 27 interleaving with annular rows of stationary directing vanes 28, suitably mounted on the walls 23 and 26 of the casing. The alternate rows of blades and 10 vanes receive motive fluid from the port 24 and communication is provided between each side of the rotor by a series of openings 29 arranged at the base of the rotor 22, adjacent to the shaft of the turbine. 15 The port 24 of the secondary stage 6 communicates directly with the receiving chamber 13, while each port of the stages 7, 8 and 9 communicate with an annular chamber 31, formed between the rear wall 26 of one 20 stage casing and the forward wall 23 of an adjacent stage. Each stage 6, 7, 8 and 9 communicates with a common exhaust passage 32, which is formed within the casing 10 and communicates with the exhaust port 25 (not shown).

The chamber 31 of the respective stages 7, 8 and 9 communicates with a valve chamber 33 through the corresponding passages 14, 15 and 16. The valve chamber 33 communicates with the receiving chamber 13 and is provided with a piston valve 34, which is actuated by a governor 35, with which the turbine is provided. Ports 36, 37 and 30 are arranged in the piston valve 34 and 35 are adapted to communicate with the respective passages 14, 15 and 16 for certain positions of the piston valve and to admit motive fluid from the receiving chamber 13 to the corresponding stage. The piston 40 valve is adapted to open the passages 14, 15 and 16 successively and to admit motive fluid to the secondary stages in accordance with the load demand of the turbine.

The nozzles 12 are divided into groups 5 38, 39, 40 and 41 of a suitable number each and each group is inclosed within a chamber 43, which communicates with a motive fluid supply passage 44 through a port 45. The motive fluid supply passage 44 communicates with a motive fluid inlet port 50, 50 formed in the casing 10. A valve mechanism 46, adapted to regulate the flow of motive fluid through the port 45, comprises a valve disk 47, mounted on a valve stem 48, 55 which is connected to a differential piston 49 of the valve-operating mechanism. The piston 49 is located in the cylinder 51, which is bored to two diameters to correspond to the different diameters of the piston 49. A 60 restricted port 52 extends through the piston 49 and admits motive fluid to a chamber 53 above the piston, and the lower and smaller face of the piston is exposed to the fluid pressure of the supply passage 44. An 65 annular chamber 54 is formed in the casing

of the cylinder 51 adjacent to the ring formed by the different diameters of the differential piston 49 and communicates with the atmosphere through a port 55. Under such conditions the disk 47 is normally held to its seat on the walls of the 70 port 45 by the fluid pressure in the chamber 53, which acts above the piston 49 in opposition to the fluid pressure of the passage 44 on the lower face of the piston.

The top portion of the chamber 53 communicates with a cylinder 56 of a governor-controlled relay device through a tube 58. The cylinder 56 communicates with the exhaust passage 32 through a pipe or passage 80 59 and is provided with a governor-operated piston 61, which is adapted to open and close ports 62, 63, 64 and 65 to the exhaust pipe 59. The valve chamber 53 of the valve-operating mechanism of each of the groups 85 38, 39, 40 and 41 respectively communicate with the ports 62, 63, 64 and 65 through the separate tubes or passages 58. The piston 61 is provided with a piston rod 66, which extends through a suitable gland in 90 the end wall of the cylinder 56 and connects with a lever 67, which is fulcrumed at 68 on the casing 10 of the turbine and which is attached to a governor-actuated sleeve on the governor standard. A link 69 is attached 95 to the lever 67 at 71 and to a lever 72, fulcrumed on a rod 73, which is journaled in suitable brackets formed integrally with the casing 10. A lever 74 is rigidly mounted on the rod 73 and operates the piston valve 100 34 through a valve stem 75.

The governor 35, the controlling valves of the nozzle groups 38, 39, 40 and 41 and the piston valve 34 are so arranged that the number of nozzle groups effective in delivering motive fluid to the turbine and the number of secondary stages communicating with the receiving chamber 13 of the turbine is varied in accordance with the load demand or the speed of the turbine.

During the normal operation of the turbine, the nozzle-controlling relay device is so arranged that the port 62, which extends through the casing of the cylinder 56 and which communicates with the chamber 53 of the groups 39 is opened to the exhaust. The port 52, through which steam is admitted to the chamber 53 from the fluid supply passage 44, is of such size, relative to the exhaust port 62, that the flow of motive fluid through the chamber will be unrestricted and the pressure will consequently drop and permit the valve disk 47 to be raised by the fluid pressure on the under side of the piston 49, thereby admitting steam to the turbine through the nozzles of the group 38. As the load increases and the speed of the turbine decreases, the governor 35 will move the piston 61 to such a position that the 110 115 120 125 130 piston 49 is located in the cylinder 51 such that the fluid pressure on the lower face of the piston 49 is greater than the pressure on the upper face of the piston 49, thereby holding the piston 49 in its seat on the walls of the port 45.

port 63 will also communicate with the exhaust and the controlling mechanism of the nozzles of the group 39 will raise the valve disk 47 and admit motive fluid to the turbine 5 through the nozzles of the group 39. The piston valve 34 and its operating links and levers are so arranged that the passage 14 will communicate with the receiving chamber 13 and admit motive fluid to the secondary stage 7 when the nozzles of the group 39 are admitting motive fluid to the turbine. As the turbine continues to decrease in speed, the nozzle groups 40 and 41 are successively opened to the motive fluid supply 15 passage 44 and the ports 37 and 30 of the piston valve 34 successively open the passages 15 and 16 respectively and admit motive fluid from the receiving chamber 13 to the corresponding secondary stages. Finally 20 at a predetermined reduction in speed of the turbine, all the nozzles are open and supplying motive fluid to the turbine and all the secondary stages are in communication with the receiving chamber and operating 25 under full pressure.

The ports 24 of the secondary stages are of such a size that each will effectively convey the expanded motive fluid admitted to the turbine by one group of nozzles and since 30 an additional stage is rendered effective as a working agent of the turbine as each group of nozzles is opened, it is apparent that the turbine will have a wide range of efficient operation. Each secondary stage is directly 35 connected to the exhaust passage 32 and will, therefore, add substantially no resistance while running idle, as the rotor element will be revolving in a vacuum.

A number of separate valves, either directly 40 operated by the governor or an auxiliary relay device, may be substituted for the piston valve 34 and various methods may be utilized for controlling the valves of the separate nozzle groups and, while I have 45 illustrated my invention as embodied in a turbine utilizing an impulse section as an initial stage and a plurality of secondary stages in which the motive fluid is fractionally expanded throughout a number of alternate rows of moving blades and stationary vanes, I wish it to be specifically understood that I do not limit myself to the arrangement shown and described, and that any type, or any combination of types, may 50 be utilized and still fall within the spirit and scope of my invention.

What I claim as new and useful and desire to secure by Letters Patent is:

1. In an elastic fluid turbine, an initial stage, a plurality of secondary stages and speed responsive means for varying the number of secondary stages communicating with said initial stage.
2. In an elastic fluid turbine, an initial stage, a plurality of secondary stages in

combination therewith, means for varying the motive fluid supplied to said initial stage and for varying the number of secondary stages communicating therewith in accordance with the load demand.

3. In an elastic fluid turbine, the combination of a plurality of governor-controlled supply nozzles, an initial stage communicating therewith, a plurality of secondary stages and governor-controlled means for putting said secondary stages into communication with said initial stage.

4. In an elastic fluid turbine, an initial stage, a plurality of secondary stages, a plurality of valves admitting motive fluid to said initial stage, governor controlled means for successively operating said valves and means, operating simultaneously with said valves, for successively opening communication between said initial stage and said secondary stages.

5. In combination with a high-pressure turbine element, a low-pressure turbine element receiving fluid exhausted from said high-pressure turbine element, and speed responsive means for by-passing a portion of said fluid around said low-pressure turbine element.

6. In combination with a high-pressure turbine element, a low-pressure turbine element receiving motive fluid from said high-pressure turbine element, a second low-pressure turbine element and speed responsive means for by-passing exhaust fluid from said high-pressure turbine element around the first of said low-pressure turbine elements to said second low-pressure turbine element.

7. In combination in a turbine, an initial stage, a plurality of secondary stages and governor controlled means for varying the number of secondary stages effective as working agents.

8. In combination in a turbine, an initial stage, a plurality of secondary stages, a plurality of admission valves for said initial stage, a governor controlling mechanism for controlling the operation of said valves and governor controlled means for rendering one or more of said secondary stages effective as working agents of said turbine.

9. In an organized apparatus, a high pressure turbine, a plurality of low pressure turbines operating on a common shaft, a common exhaust for said low pressure turbines and means, dependent on the load on said apparatus, for varying the number of low pressure turbines effective as working agents.

10. In an elastic fluid turbine, an initial stage, a plurality of secondary stages receiving motive fluid therefrom, means for controlling the delivery of fluid to said secondary stages and means whereby, when the inlet to one of said stages is closed, the rotor element of said stage is caused to operate in a vacuum.

11. In combination in an elastic fluid turbine, an initial stage, a plurality of secondary stages communicating therewith, independent inlet ports for said secondary stages, means, dependent on the speed of said turbine, for controlling the admission of fluid to said inlet ports and means whereby, when the inlet to one of said secondary stages is closed, said stage is subjected to vacuum pressure.
12. In combination with a source of exhaust steam supply, a plurality of turbines adapted to operate in parallel relation on steam from said supply, and a governing device for automatically controlling the supply of steam to said turbines.
13. In combination with a high pressure turbine, a plurality of low pressure turbines receiving motive fluid therefrom and provided with a common shaft and a speed responsive means for controlling the delivery of motive fluid to the low pressure turbines.
14. In an organized turbine, a plurality of rotor elements constituting stages and mounted upon a common shaft, means for operating said stages in parallel with the same initial and exhaust pressures, and a governing device for automatically controlling the operation of said means.
15. In an organized turbine, two or more rotor elements mounted upon a common shaft, means for operating said elements in parallel with the same initial and exhaust pressures, a high pressure turbine element, and means for automatically distributing the exhaust from said high pressure turbine element to one or more of said elements operating in parallel.
16. In combination with a high pressure turbine element, two or more low pressure turbine elements having a common exhaust, and speed responsive means for distributing the exhaust motive fluid from said high pressure turbine element to said low pressure turbine elements so that one or more may operate in series with said high pressure element and two or more in parallel one with the other.
17. In combination with a high pressure turbine element, a plurality of low pressure turbine elements, and speed responsive means for causing said low pressure turbine elements to operate in series with said high pressure turbine element and in parallel one with the other.
18. In combination in a multi-stage turbine, a plurality of stages operated in parallel, independent inlets and a common exhaust for the stages and means, dependent on the load on the turbine, for controlling the delivery of motive fluid to said stages.
19. In a multi-stage elastic fluid turbine, a plurality of stages operating in parallel, independent inlets and a common exhaust for the stages and means, dependent on the load on the turbine, for automatically rendering one or more of said stages effective as a power delivering element of the turbine.
20. In combination in a multi-stage turbine, a plurality of stages, the rotor elements of which are mounted on a common shaft, independent inlets and a common exhaust for the stages and means for varying the number of stages effective as working elements of the turbine.
21. In combination with a fluid impelled motor, a plurality of turbine elements receiving motive fluid therefrom and provided with a common exhaust and means, dependent on the load, for controlling the delivery of fluid to said motor and to said turbine elements.
22. In combination with a fluid impelled engine, a plurality of turbine elements adapted to receive motive fluid therefrom and speed responsive means for rendering one or more of said elements effective as power delivering agents.
23. In combination with a fluid impelled engine, a plurality of turbine elements receiving motive fluid therefrom and operating in parallel and means, dependent on the load, for rendering one or more of said turbine elements effective as power delivering agents and for imposing the governing function upon one of said elements.
24. In combination with a fluid impelled engine, a plurality of turbine elements receiving motive fluid therefrom, a common exhaust and independent admission ports for said elements and means, dependent on the load, for delivering motive fluid to one or more of said elements and imposing the governing function upon one of said elements.
25. In combination with a fluid impelled engine, a plurality of turbine elements receiving motive fluid therefrom and speed responsive means for controlling the delivery of motive fluid to said engine and for proportioning the motive fluid to said elements.
26. In combination with a high pressure turbine element provided with a governing device, of a plurality of low pressure turbine elements adapted to operate in parallel one with the other, and in series with said high pressure element, and a governing device for distributing the exhaust motive fluid from said high pressure element to said low pressure elements.
27. In combination with a high-pressure turbine element, two low pressure turbine elements, conduit means for delivering exhaust motive fluid from said high-pressure element around one of said low-pressure elements and to the other of said low-pressure elements, and speed responsive means for controlling said conduit means.

28. In combination with a high-pressure turbine element, two or more low-pressure turbine elements, conduit means for leading the exhaust from said high-pressure element to said low-pressure elements, valve mechanism for controlling said conduit means, and a speed responsive device for governing said mechanism.

29. In combination with a source of exhaust steam supply, a plurality of turbines adapted to operate in parallel relation on

steam from said supply, and a governing device for automatically distributing the steam to said turbines.

In testimony whereof, I have hereunto 15 subscribed my name this 28th of March, 1906.
